UNITED STATES PATENT OFFICE

EDWARD H. CRAIGE, OF BROOKLYN, NEW YORK, AND FRANK HENRY, OF PHILADELPHIA, PENNSYLVANIA.

BINDER ATTACHMENT FOR SEWING-MACHINES.

SPECIFICATION forming part of Letters Patent No. 275,889, dated April 17, 1883.

Application filed November 18, 1881. (No model.)

To all whom it may concern:

Be it known that we, EDWARD H. CRAIGE, a resident of the city of Brooklyn, Kings county, New York, and FRANK HENRY, a resident of 5 Philadelphia, Pennsylvania, both citizens of the United States, have invented certain new and useful Improvements in Sewing-Machine Attachments, of which the following, taken in connection with the drawings, is a specification.

Our invention consists of a binding attachment for sewing-machines, supported within or upon a holder in a manner permitting of a change of position by turning in its seat or 15 socket, whereby the article or material to be operated upon is delivered to the needle in different positions, as will be hereinafter more fully set forth.

In the drawings, Figure 1 represents our improved sewing-machine attachment. Fig. 2 represents the binding-guide with its ear by which its position is changed; Fig. 3, a sectional end view, showing socket and binding-guide in position.

25 A is the binding-guide proper, containing a channel-way for forming the fold or folds, supported within a pocket or opening forming a seat with which the frame C' is provided, and within which pocket or seat the guide is rotated by hand, as desired, by means of an ear or projection with which the guide proper is provided, (shown at B in the drawings.) The opening within which the edge of the article to be bound is passed is shown at a in the 35 drawings.

The operation of this guide is as follows: When desirable to fold the binding over the edge of the article being bound unevenly, or, in other words, to have the binding lap farther 40 upon the surface of the cloth upon one side than upon the other, the operator turns the

guide A in its seat by turning the projection or ear B and pushing it in the desired direction, and to the extent required to cause the one edge of the folded strip to overlap the 45 other. By this the operator is enabled to vary the overlap of the edges of the braid or other material forming the binding to most any extent desirable in practice.

The guide is represented as attached to and 50 supported by the presser-bar of a sewing-machine at C" above the cloth-plate, whereby a greater range for operation is secured. It is obvious, however, that the guide attachment may be held and secured upon the cloth-plate 55 of the machine in the usual manner well known to those accustomed to use sewing-machine attachments.

The formation of the binding-guide proper is so well understood that a description would 60 seem superfluous.

Having thus set forth our invention, what we claim as new, and desire to secure by Letters Patent of the United States, is—

1. The combination, with a socketed frame 65 adapted to be held detachably upon a sewing-machine, of a guide adapted to rotate in said socket-frame, and adapted to present the folded strip to form a hem, a fold, or both, in different positions to the needle, substantially 70 as and for the purpose set forth.

2. The combination, with a socketed holder and binding-guide, substantially such as described, of a projection secured to said guide, whereby its position may be changed, substantially 75 as and for the purpose set forth.

EDWARD H. CRAIGE.
FRANK HENRY.
